UNITED STATES PATENT OFFICE.

CAESAR A. RODNEY AND JOHN M. C. RODNEY, OF WILMINGTON, DEL.

DEVICE FOR MANUFACTURING PAPER SHOT-SHELLS.

SPECIFICATION forming part of Letters Patent No. 237,701, dated February 15, 1881.

Application filed July 7, 1880. (No model.)

To all whom it may concern:

Be it known that we, CAESAR A. RODNEY and JOHN M. C. RODNEY, both of Wilmington, in the county of New Castle and State of Delaware, have invented a certain new and useful improvement in Apparatus for Manufacturing Paper Shot-Shells, of which the following is a specification.

Our invention relates to machines for manufacturing paper cartridge-shells composed of a tube of paper, a metallic head, and a paper wad or base, more especially to such as are shown in Patent No. 125,508, granted to C. S. Wells, April 9, 1872, and in an application for Letters Patent filed by us on the 19th of April, 1879; but it is also applicable to machines in which the punch or header enters the die and upsets the flange on the shell.

In our application above referred to an apparatus for making paper cartridge-shells is shown, which is capable of producing uniformly-perfect shells irrespective of ordinary variations in the bulk of the paper wad and in the thickness of the paper tube.

In machines in which the punch enters the die it is necessary to have the paper wad of a uniform bulk, as any excess will cause the metal flange to fin or flow between the punch and walls of the die.

In practice it is impossible to have the wads and tube of a uniform bulk, and therefore much bad work is produced and considerable waste of material caused.

The object of our invention is to provide for this variation in material, and to produce uniformly-perfect shells irrespective of such irregularities in the bulk of the wad and tube as would ever occur in practice.

Our invention consists in providing an elastic support for the pin or mandrel on which the cartridge is compressed, so that when a certain amount of pressure has been reached the mandrel will yield, and thus prevent the flange of the shell from finning.

The accompanying drawing is a central sectional view of a cartridge-die such as shown in our above-mentioned application, showing part of the dial and bed-plate of a cartridge-press and the yielding support for the mandrel.

In the construction shown in the drawings a series of dies, A, will be arranged in the re-

volving dial B of a press, so that the pins or mandrels C of said dies will move loosely upon the bed-plate D, as fully shown and described in our application above mentioned, and as is well understood.

Immediately beneath the header E of the press there is a vertical opening in the bed-plate D. A supporting head or bolt, F, fits snugly in this opening, so as to be capable of moving freely up and down therein, and has upon its lower end a nut, f, by which it can be adjusted so that its upper end will be flush with the surface of the bed-plate. This head or bolt is supported by bar or plate springs G, of the requisite strength, mounted upon bolts H depending from the bed-plate. By means of nuts h upon the bolts H the upward pressure of the springs upon the supporting-head can be regulated as may be desired.

The die shown in the drawing is supported by a spring, a, so as to yield as the header descends, its upward rise being limited by the flange a'. It is obvious, however, as before stated, that our invention is equally applicable to non-yielding or stationary dies which are entered by the punch.

As the dial of the press pauses under the header the mandrel will rest solely upon the supporting-head. The header then descends and compresses the cartridge. The mandrel will yield only when the compression of the wad between it and the header exceeds the strength of the spring which supports the head or bolt upon which it rests. This spring must therefore be of sufficient strength to insure the proper compression of the wad and its requisite lateral expansion to fill the flange of the shell, conform it to the recess in the die, and solidly compact the wad therein. It will be obvious that the force of this spring can be so regulated that the flanges of the shells will never fin or flow, and that at the same time strong compact cartridge-shells having bases of equal solidity can uniformly be produced.

A further advantage of our invention is that as the mandrel will yield the crank of the press will be relieved from the strain which would be caused by an unusually large wad.

Again, where the pin is stationary and an extra large wad is used the tube is liable to be cut off by the pressure at the edge of the brass.

This objection is obviated by the use of the yielding mandrel.

Instead of having one spring beneath the header of the press, it might be desirable to place a spring beneath each mandrel in the dial, so that the whole apparatus would revolve upon the bed-plate.

It will be obvious that the details of construction herein described may be varied without departing from the spirit of our invention.

Having thus described our invention, what we claim as new, and desire to secure by Letters Patent, is—

1. The combination of a cartridge header or punch, a yielding or non-yielding die, and a yielding pin or mandrel, substantially as set forth.

2. The combination, substantially as hereinbefore set forth, of the bed-plate, the die, the pin or mandrel, the supporting head or bolt, and the spring which supports the head or bolt.

3. The combination, substantially as hereinbefore set forth, of the punch or header, the revolving dial, a series of dies having loose mandrels thereon in said dial, the bed-plate 25 upon which the dial revolves, the mandrel-supporting head or bolt, and the spring which supports said head or bolt.

4. The combination of the bed-plate, the mandrel-supporting head or bolt, the adjusting-nut upon its lower end, the spring which supports said head or bolt, the bolts which support the spring, and the nuts for adjusting it, for the purpose set forth.

In testimony whereof we have hereunto subscribed our names.

CAESAR A. RODNEY.
JOHN M. C. RODNEY.
